WATER SAFETY BELT

Clarke F. Hine, Chicago, Ill., assignor, by mesne assignments, to The Brunswick-Balke-Collender Company, Chicago, Ill., a corporation of Delaware

Filed Aug. 5, 1957, Ser. No. 676,122

2 Claims. (Cl. 9—336)

My invention relates to a safety belt for swimmers particularly for use in water skiing, boating, bathing, and in any situation where a swimmer may need a buoyant support in learning to swim or being thrown into the water from a boat, or the like, and has for its primary object the provision of a safety belt which assists in supporting the body of a wearer preferably in a vertical position in the water and if the wearer tilts his body to an elongated position, the belt is so constructed and arranged that the support comes from the front and rear of the body with freedom for movement of the arms for swimming movement in the water, particularly water skiing, and the like.

Another and further object of my invention is the provision of a safety belt which comprises a pair of buoyant pads secured together, one of which is arranged to be worn across the body of the wearer at the small part of the back and the other pad worn across the lower part of the chest and upper part of the abdomen of the wearer which is partially held against upward movement by the rib cage of the wearer, while the pad at the rear is held across the small of the back with the hips of the wearer preventing downward slippage of the pad at the rear of the body, thus providing a safety belt which remains firmly in position about the body of the wearer and because there is no padding at the sides of the body, the belt does not materially restrict the movement of either the arms or legs of the wearer for swimming, water skiing, boating, and the like.

Another and further object of my invention is the provision of a safety belt for swimmers which comprises a pair of buoyant pads, one pad of which is worn in front of the wearer while the other pad is at the rear which pads are secured about the wearer by spaced belts which encircle the body of the wearer, one pad being stitched to one of the belts while the other pad is slidably mounted thereon, and the outer belt is stitched to the pad loosely mounted upon the first mentioned belt, and slidably mounted upon the other supporting pad, thereby providing for a freedom of adjustability of the pads about the body of the wearer without undue strain upon either the belt or the wearer or being particularly uncomfortable to the wearer.

Another and further object of my invention is the provision of a swimming belt comprising a pair of front and rear pads which terminate at the sides of the body and are connected to spaced belts so as to allow complete freedom of the arms of the wearer for swimming, movement, and the like, when the wearer is using the safety belt.

Another and further object of my invention is the provision of a safety belt which is so constructed and attached to the body of the wearer that it is particularly adaptable for water skiing and supports the body in a substantially upright position in the water permitting the easy removal of water skis from the feet of the wearer and likewise, an easy attachment of the water skis to the

2

feet of the wearer while the body is in an upright position in the water, and which also protects the body of the wearer from water shocks if the wearer is thrown into the water violently.

5 Another and further object of my invention is the provision of a safety belt which is easily and quickly attached to the body of the wearer and which can be easily detached therefrom and the belts tightened while on the body of the wearer and the support pads adjusted 10 accordingly, but in which, once the support belt is drawn taut, the pads remain in fixed position on the belt and also about the body of the wearer.

The invention will be more fully and better understood by reference to the accompanying drawings and in 15 which—

Figure 1 is an elevational view of my improved safety belt in extended position; and

Figure 2 is a perspective view of the safety belt shown in the position it occupies when in place upon the body 20 of the wearer.

Referring now specifically to the drawings and in which like reference characters refer to like parts throughout, a pair of pads 10 and 11 are shown, the pad 10 having transversely extending tapes 12, 12 thereon at each of 25 its ends with an intermediate transversely extending tape 13 being provided, the tapes 12, 12 and 13 being stitched or otherwise secured to the outer covering of the pad 10 throughout the body thereof with cross stitching 14 near the ends and other rows of cross stitching 15, 15 30 being provided whereby loops 16, 16 are provided through which the belt 17 extends so that the pad 10 is freely movable on, and the belt 17 can be threaded through the loops 16, 16 formed in the transverse tapes 12, 12 and 13. A second belt 18 is provided spaced from the 35 belt 17 which overlays the ends of the tapes 12 and 13 and is stitched thereto by rows of stitching 19, 19 which stitching also extends through the outer fabric wall of the pad 10 so that the belt 18 is fixed to the pad 10 and cannot be moved with respect to the pad 10. A ring 20 40 is fixed to one end of the belt 18 while a slide 21 is movably mounted upon the free end of the belt 17 with a snap 22 thereon which is adapted to engage a ring 23 fixed at the opposite end of the belt 17. The free end of the belt 18 has a similar slide 21 mounted thereon 45 with a fixed snap 22 which is adapted when the belt is worn about the body of the wearer to engage in the ring 20 with the slides 21, 21 being movable on the free ends of the belts 17 and 18 respectively, when these belts are loosely looped, but which grips the belts tightly when the belts are drawn taut and particularly when they are wet.

50 The support pad 11 has transversely extending end tapes 24, 24 thereon with an intermediate transversely extending tape 25 stitched to the outer covering thereof, the said tapes 24, 24 and 25 underlying the belt 17 at one 55 of their ends with the belt 17 being stitched to the outer fabric covering forming the pad 11 by rows of stitching 26, 26 which stitching extends over the ends of the transversely extending tapes 24 and 25 with the tapes 24 and 25 adjacent the belt 18 also being stitched at 27, 27 inward from their outer ends to the inner face of the outer covering of the pad 11, with the ends of the tapes 24, 24 and 25 being stitched to the pad 11 by stitching 28, 28 whereby loops 29, 29 are formed in the tapes 24, 24 and 25 through which the belt 18 extends whereby the pad 11 is 60 freely movable longitudinally on the belt 18, but is firmly stitched to the belt 17 so that the pads 10 and 11 are 65 freely movable upon either of the belts 17 or 18 so that one pad and one belt are fixed together but are movable as a unit relative to the other pad and the other belt.

70 The pads 10 and 11 have an outer fabric covering 30, 30 thereover of a closely woven material with each of said pads 10 and 11 having a vinyl inner envelope 31 which

is filled with a buoyant material 32 such as kapok or other buoyant material with the vinyl covering 30 being electrically heat-sealed around the kapok filling 32 with the vinyl covering being waterproof so that after being heat-sealed, on its mating edges, water does not penetrate into the kapok filling causing it to deteriorate by rotting or causing it to lose its buoyancy by becoming soaked with water, or the like, so that regardless of the time in which the wearer may remain in the water wearing the safety belt, the safety belts retain their buoyancy unless the vinyl covering is cracked, or snagged in some fashion allowing water to soak into the kapok.

The application of the belt to the body of a wearer can be easily and quickly accomplished by simply wrapping the device around the body and securing the snaps 22 and the rings 20 together, after which the slides 21, 21 can be moved on the belts 17 and 18 so as to hold the belts snugly in position about the body of the wearer and at the same time, the pads can be positioned across the front of the body and at the rear centrally of the body so that the ends of each of the pads terminate at the sides of the body, leaving only the belts at the sides of the body of the wearer so that the pads do not interfere in any way with the movement of the arms in swimming, and the like, and for use of the hands and arms particularly in water skiing and holding on to the pull ropes by means of which the skiers are drawn over the surface of the water and also leaves the arms and hands free for adjustment of the skis and freedom of swimming as desired. In the adjustment of the pads, the fact that each of the pads is slidably connected with one of the belts while being secured firmly to the other belt, allows a relative movement of the pads with respect to each other and an easy adjustment of the pads to a proper position on the body of the wearer and at the same time the pads are not easily displaced and because they are firmly anchored to opposite belts, they remain firmly in position about the body of the wearer, particularly after the belts become wet. Likewise, when the belts become wet, they do not move through the slides 21 easily and, therefore, the belts are firmly held about the body of the wearer and because of the fact that the front pad is over the upper part of the abdominal cavity and the rear pad extends over the small part of the back of the wearer, movement of the pads longitudinally of the body of the wearer is most unlikely to occur. At the same time, in case of an emergency, or the like, the snaps can easily be loosened from the rings 20 and the belt removed, while the wearer is in the water and replaced if desired. The belt is made in

varying sizes and in the small size, the pads are sufficiently buoyant to sustain the body of an eighty pound person in the water while in the large size, the pads are sufficiently large to sustain the weight of a one-hundred pound person in the water without being unduly bulky or interfere with the movement of the wearer while in the water to any great extent.

While I have described more or less precisely the details of construction, I do not wish to be understood as limiting myself thereto, as I contemplate changes in form, the proportion of parts and the substitution of equivalents as circumstances may suggest or render expedient without departing from the spirit or scope of the invention.

What is claimed is:

1. A water safety belt comprising separate front and rear buoyant pads, rows of spaced loops along the upper edge on the inner face of one of said pads and along the lower marginal edge of the other of said pads, along its inner face, a belt adapted to encircle the body of a wearer secured for a substantial portion of its length to the inner face of one of said pads adjacent the edge of the pad opposite the said loops, and extending through the loops upon the other of the said pads, a second belt secured for a substantial portion of its length adjacent one of its ends to the inner face of other of said pads along the edge of the pad opposite the loops, the second mentioned belt extending through the loops adjacent the marginal edge of the companion pad, and fastening means on the free ends of the said belts.
2. A water safety belt comprising separate front and rear buoyant pads, rows of spaced loops attached to the inner face of one of said pads along the upper edge of the said pad and along the lower marginal edge of the inner face of the other of the said pads, a belt adapted to encircle the body of the wearer secured for a substantial portion of its length to the inner face of one of said pads adjacent its edge opposite the said loops, and extending through the said loops upon the other of the said pads, a second belt secured for a substantial portion of its length adjacent one of its ends to the inner face of the other of said pads adjacent its edge opposite the loops and extending through the loops adjacent the marginal edge of the companion pad, and fastening means on the free ends of each of said belts, the said loops and belts being on the sides of the pads adjacent the wearer.
